2 Claims. (Cl. 315—233)

The present invention relates to a voltage divider for the intermediate electrodes in an anode unit in a high voltage gas-filled rectifier.

It is already known to connect the intermediate electrodes of an anode unit in a high voltage gas-filled rectifier to a voltage divider comprising a chain of the capacitors and resistors connected in series and inserted between the anode and the cathode of the gas-filled rectifier. It is observed that in voltage dividers of the known art, disturbances may arise during the ignition of the rectifier. It has been very difficult to establish the cause of these disturbances but the primary cause seems to be that it takes a certain time for the arc to extend from the cathode via the intermediate electrodes to the anode. As the arc extends from the cathode and reaches the intermediate electrodes, the capacitors between said intermediate electrodes and the cathode of the rectifier will discharge through the arc. Owing to the fact that the extension of the arc from the cathode to the anode takes a certain, even if it is a very short time, the discharge time will be longer for the capacitors nearest to the cathode so that these capacitors are more discharged than the capacitors nearer to the anode. If a sudden change in the voltage of the anode of the rectifier arises before the arc has reached the anode, by way of example, because a parallel operating rectifier has ignited, so that the voltage between the anode and the cathode is short-circuited, this voltage jump is absorbed by the resistors in the capacitor-resistance chain in proportion to their resistances. As external voltages of different frequencies coming from outside the rectifier ought to be distributed during normal operation as equally as possible between the intermediate electrodes, the resistors of the known voltage dividers are equally distributed in the capacitor-resistor chain. A voltage jump arising at the ignition of the rectifier will thus be equally distributed between the intermediate electrodes. As the capacitors, however, as mentioned above, are at this time unequally discharged and thus have unequal voltages the consequence is that the voltage distribution between the different intermediate electrodes is such that for certain adjacent intermediate electrodes, the electrode nearer the anode will have a more negative potential than the electrode nearer to the cathode, which gives a disturbance at the ignition of the rectifier. The ignition time is thereby extended and the current distribution between parallel operating anodes is rendered considerably more difficult and possibly quite spoiled.

These drawbacks are avoided by the present invention, which is characterised in that the resistors are unequally distributed along the capacitor-resistor chain of the voltage divider so that the part of this chain nearer to the anode of the rectifier has greater resistance than the part nearest to the cathode. Consequent to this the greater part of a voltage jump in the anode voltage will be distributed between the intermediate electrodes nearest to the anode and the smaller part of the voltage jump between the electrodes nearest to the cathode. With a suitable distribution of the resistances in the resistor-capacitor chain, it is possible in this way to obtain a suitable distribution of the potential between the intermediate

2

electrodes so that no disturbances in the ignition of the rectifier will arise. The resistors in the capacitor-resistor chain may, according to the invention, suitably be voltage dependent resistors as the deviation caused by the invention from the desired equal distribution of external voltage during normal operation is thereby limited.

The invention will be further explained in the following with reference to the accompanying drawing showing a form of the invention.

10 In the drawing is shown a gas-filled rectifier 1 with an anode 2, a cathode 3 and a number of intermediate electrodes 4. A voltage divider is connected between the anode and the cathode and consists of a capacitor-resistor chain 5 in parallel with a purely resistive resistor chain 6. 15 The capacitor-resistor chain 5 consists of a number of capacitors 7 and resistors 8, 9, 10, 11. The resistor-capacitor chain 5 and the resistor chain 6 are parallel connected and have a number of transverse connections, and the resistor chain 6 is connected to the intermediate electrodes 4 via series resistors 12. The main purpose of the resistor chain 6 is to give series resistances in the connections to the intermediate electrodes 4 and to reduce the number of required capacitors 7 in the capacitor-resistor chain. When an arc extends from the cathode 3 20 towards the anode 2 the capacitors 7 of the capacitor-resistor chain 5 between the cathode and the intermediate electrodes reached by the arc will discharge in relation to the extension of the arc. When the arc has reached the intermediate electrodes 4 nearest to the anode, the capacitors nearest to the cathode are discharged more than the capacitors near to the anode and have thus a lower voltage than said last mentioned capacitors. If now a sudden decrease in the anode voltage arises, by way of example, caused by the ignition of a parallel operating rectifier, 25 this voltage reduction in the first moment will be distributed on the resistors 8, 9, 10 and 11 in the capacitor-resistor chain. According to the invention these resistors are unequally great so that the resistor 8 is the greatest and the resistor 11 the smallest. As the voltage jump is 30 distributed between the resistors in relation to the resistances a greater part of the voltage jump is absorbed by the resistor 8, a smaller part by the resistor 9 and a still smaller part by the resistor 10 and the smallest part by the resistor 11. Owing to this the differences of the 35 voltage of the capacitors 7 caused because the capacitors nearest to the cathode are more discharged than the capacitors nearest to the anode, are compensated so that a suitable distribution of the potential on the intermediate electrodes 5 is reached in spite of the voltage jump occurring, and the ignition can be carried out without disturbances.

We claim:

1. Voltage divider for an anode unit for a high voltage gas-filled rectifier; said anode unit provided with a number of intermediate electrodes, said intermediate electrodes connected to said voltage divider; said voltage divider comprising resistors and capacitors; said resistors and capacitors connected in series between the anode and the cathode of the rectifier; the resistances of said resistors being unequally distributed along the voltage divider in such a way that the part of the voltage divider nearest to the anode has greater resistance than the part nearest to the cathode.

2. An arrangement as set forth in claim 1, said resistors being voltage dependent resistors.
